UNITED STATES PATENT OFFICE.

JOHN P. KLINE, OF BROOKLYN, MICHIGAN.

FELT BOOT.

No. 870,037.

Specification of Letters Patent.

Patented Nov. 5, 1907.

Application filed February 4, 1907. Serial No. 355,647.

To all whom it may concern:

Be it known that I, JOHN P. KLINE, a citizen of the United States, residing at Brooklyn, in the county of Jackson and State of Michigan, have invented a new 5 and useful Felt Boot, of which the following is a specification.

This invention relates to felt boots of that type which are worn inside of arctics or rubber overshoes. These boots, as commonly made, are objectionable 10 for the reason that no provision is made for preventing snow from entering between the uppers of the overshoe and leg portion of the felt boot. The snow that is thus gathered into the pocket formed between the overshoe and boot melts and causes the dampness 15 to penetrate the fabric so that the foot becomes cold and wet. Furthermore, the felt, after once becoming wet, is soft and loses its original form.

The present invention has for one of its objects to provide a protector or snow excluder for covering the 20 opening around the felt boot at the uppers of the overshoe.

A further object of the invention is the provision of a combined felt boot and overshoe having a protector of suitable flexible material, such as leather, secured 25 to the leg of the boot and fitted over the overshoe, an elastic strip being included in the protector so as to hold it snugly around the upper of the overshoe.

Another object of the invention is the employment 30 of a wearing piece under the elastic so as to prevent the buckle of the overshoe from destroying the elastic by constant wear and rubbing.

With these objects in view, and others, as will appear as the nature of the invention is better understood, the invention comprises the various novel features 35 of construction and arrangement of parts, which will be more fully described hereinafter, and set forth with particularity in the claims appended hereto.

In the accompanying drawing, which illustrates one of the embodiments of the invention, Figure 1 is a perspective view of a combined felt boot and overshoe, portions being broken away to better illustrate the details. Fig. 2 is a front perspective view showing the 40 protector and snow excluder turned up to show the different features of construction. Fig. 3 is a horizontal section of the front part of the protector. Fig. 4 is a vertical sectional view of the protector illustrated in Fig. 1 showing the manner of fastening the protector to the buckle or clasp.

Corresponding parts in the several figures are indicated throughout by similar characters of reference.

Referring to the drawing, 1 designates a felt boot and 45 2 a rubber overshoe, both of ordinary construction. The protector and snow excluder comprises a body of fabric 3, such, for instance, as leather, that extends 50 around the boot 1 and projects part way into the overshoe, and the ends of that portion of the leather body 3

that is outside of the overshoe are connected by an elastic strip 4. The body of leather 3 is preferably secured to the felt at a point adjacent the upper edge of the overshoe by one or more rows of stitching 5, the lower 55 or free edge of the leather protector being folded inwardly and secured by a similar row of stitching 6. The portion of the combined protector and snow excluder that is outside the overshoe is intended to be turned down over the upper of the overshoe, so as to form a 60 complete closure for the space between the felt boot and upper of the shoe. The elastic piece 4 is arranged at the front and extends over the buckle 7 and, in order to prevent the buckle from wearing the elastic away, a 65 flexible shield 8 underlies the elastic. This shield is 70 preferably a piece of soft leather and has its edges secured to the body 3 by stitches 9. The shield 8 has sufficient fullness to permit the elastic to stretch without interference. The elastic 4 is secured to the body 75 3 by a double row of stitches 10 one row of which serves to retain the flexible shield 8 in position. By arranging the elastic at the front of the shoe, the combined protector and snow excluder can be turned up to permit the buckle 7 to be opened or closed, as in putting on and taking off the boot.

Secured to the inner surface of the flexible shield 8 is a hook 11 which engages the frame of the buckle or clasp 7 when the protector is folded downwardly over the rubber and serves to prevent the protector from riding up at the front of the boot, there being a tab or 85 finger piece 12 secured to the rear of the protector by means of which the wearer may elevate the protector thereby to permit the removal of the rubber or overshoe.

Attention is called to the fact that by having the protector folded downwardly over the clasp or buckle 7 the latter is effectually housed and prevented from becoming accidentally released. It will also be observed that the elastic strip 4 terminates short of the line of fold of the leather protector so as to prevent undue wear 95 on the elastic as well as to present a smooth continuous surface at the juncture of the protector and upper and thus insure a water and moisture proof joint between the same.

From the foregoing description, taken in connection with the accompanying drawing, the advantages of the construction will be readily understood by those skilled in the art to which the invention appertains, and while I have described the principle of operation of the invention, together with the device which I now consider to 100 be the best embodiment thereof, I desire to have it understood that the device shown is merely illustrative, and that various changes may be made, when desired, as are within the scope of the claims.

While the protector is preferably formed of leather it 110 is obvious the same may be constructed of canvas, rubber, duck or any other suitable water-proof material.

What is claimed is:—

- The combination with an overshoe including a fastening device, a boot arranged within the over-shoe, a flexible protector one end of which is interposed between the over-shoe and boot and secured to the latter at a point above the upper edge of the over-shoe, the free end of the protector being foldable downwardly over the over-shoe, said protector being provided with a cut away portion disposed in alignment with the fastening device, an elastic strip secured to the protector at the cut away portion thereof, a flexible shield covering the elastic strip, and a hook secured to the shield and having its bill spaced from the

latter for engagement with the fastening device of the over-shoe when the protector is folded downwardly on the latter, said shield forming a housing for the hook and 15 fastening device.

In testimony that I claim the foregoing as my own, I have hereto affixed my signature in the presence of two witnesses.

JOHN P. KLINE.
